UNITED STATES PATENT OFFICE.

GEORGE E. PELLISSIER, OF JERSEY CITY, NEW JERSEY, ASSIGNOR TO LOUIS D. PELLISSIER, OF HOLYOKE, MASSACHUSETTS.

RAIL-JOINT.

1,099,202.

Specification of Letters Patent.

Patented June 9, 1914.

Application filed August 10, 1911. Serial No. 643,295.

To all whom it may concern:

Be it known that I, GEORGE E. PELLISSIER, a citizen of the United States, and a resident of Jersey City, county of Hudson, and 5 State of New Jersey, have invented certain new and useful Improvements in Rail-Joints, as set forth in the following specification.

This invention relates to rail joints.

10 An object of the invention is to join abutting rail-ends in a railway track in such a manner as to provide resistance against practically all strains tending to break down the joint and impair the tread line of 15 the rail.

A further object of the invention is to provide for joining abutting rails with convenience and despatch and at the same time to provide and maintain a continuous and 20 unbroken tread from one rail to the joined rail and efficient bonding for electrical purposes.

More specifically an object of the invention is to provide for the mechanical reinforcement of the abutting rails at the joint by the attachment of spanning plates to the rail feet while at the same time providing a molecular union between certain selected 25 parts of the abutting rail-ends.

30 More specifically this invention is an improvement over the invention described and claimed in my United States Letters Patent No. 997,697 granted July 11, 1911.

The above and further objects of the invention will be apparent from the following 35 claims which should be read in connection with the following specification, which specification is directed to illustrative embodiments of the invention shown in the accompanying drawings, which form a part 40 of this application in which like characters designate corresponding parts and in which,—

Figure 1 is a longitudinal section through 45 the joint in staggered planes as indicated by line I—I in Fig. 2; Fig. 2 is a cross-section through the joint along line II—II of Fig. 1; and Figs. 3, 4, 5 and 6 are each cross sections similar to Fig. 2, but each showing 50 a modified joint.

A and B indicate respectively the abutting rail ends of the railway track, each

comprising the head 1, the web 2 and the foot 3.

C indicates a joint-spanning plate mechanically connected, as by bolts or rivets 4, to span the joint J, directly to the feet or flanges 3 of the abutting rail ends A and B. In Figs. 1, 2, 4 5 and 6 this joint-spanning plate C is shown as a short length of steel 60 rail of the same configuration as the rails A and B, having likewise head, web and foot portions 5, 6 and 7, the same as the corresponding portions 1, 2 and 3 of the rails A and B. This spanning-rail, however, is 65 turned upside-down so that its foot 7 rests against the under face of the feet 3 of the abutting rail-ends A and B.

In forming the joint the rail ends A and B are brought closely together in abutting 70 relation, it being understood that the feet 3 have first been perforated for the reception of the rivets 4. The spanning-plate C has likewise been provided with perforations to correspond with the perforations in the feet 75 3. The perforations in the spanning-plate, however, are all arranged a little nearer to the joint than are the corresponding perforations for the rail-ends. The spanning-plate C is then heated so that the expansion 80 of the same causes the rivet holes to register. The spanning-plate C is then riveted or bolted fast to the rail-ends in a manner well known in the art and as illustrated in the drawings. Selected portions of the cross- 85 section of the abutting rail-ends A and B are then molecularly united. This may be accomplished by an electric welding machine but the oxy-acetylene blow-pipe process is preferred. A portion of the metal is 90 removed from each rail-end at the joint to form a trough-like channel such as the channel 8 at the head of the rail and the channel 9 at the foot of the rail. This channel is then filled in by melting a stick of steel in 95 the blow-pipe flame and causing the same to fuse and weld to the sides of the channel. This filling of metal is designated by 10 for the head of the rail and by 11 for the foot.

Before fillings 10 and 11 have cooled 100 down, they may be compacted by hammering. They may be finished off to have smooth surfaces by any abrading means such as an emery wheel. It is important

that the filling 10 at the head of the rail be finished true with the rail tread as indicated in Fig. 1 so that a continuous unbroken tread surface is provided. Upon the cooling 5 of the plate C the rail-ends A and B are forcibly drawn together so that the joint is normally under compression, while the spanning-plate C is normally under tension. In this manner disastrous tension strains 10 are relieved from the joint. The spanning-plate is also located in a preferred position to truss the joint and relieve the same from local strains due to the passage of rolling stock over the joint.

15 The joint shown in Figs. 1 and 2 is a preferred construction in which both the heads and feet of the rail-ends are molecularly united in addition to the mechanical connection provided by the spanning-plate C. Nevertheless a most effective joint is formed by omitting the molecular union for the feet of the abutting rail-ends, so that the 20 joint comprises merely the molecular union 10 for the head of the abutting rail-ends and the mechanical connection of the spanning-plate. This modification is shown in 25 Fig. 6.

It is also contemplated that the resistance 30 against shear at the joint principally supplied by the web 6 of the structure shown in Figs. 1 and 2 may be supplied by fish-plates, designated by 12 and 13 in Figs. 3 and 4. In Fig. 3 the fish-plates 12 and 13, bolted or riveted to the rails in the usual manner but 35 preferably under tension as described in my aforementioned Patent No. 997,697, supplement the strengthening of the joint given by the spanning-plate C shown in this figure as a flat steel plate 14.

40 Fig. 5 illustrates a joint similar to that described in connection with Figs. 1 and 2 except that the molecular union for the feet of the abutting rail-ends is omitted and a molecular union 15 for the abutting rail 45 webs is provided in addition to the molecular union 10 for the abutting rail-heads.

The structure in Fig. 4 shows head-portions, web-portions and foot-portions of the abutting rail-ends molecularly united and 50 the joints reinforced by the spanning-plate C and also by the spanning-fish-plates 12 and 13. To complete the joint shown in Fig. 4, molecular union at the head and foot portions or at the head or foot portions 55 alone may be effected first, with the rail-ends A and B temporarily held in place by temporary fish-plates. The molecular union 15 between the abutting rail-webs may then be completed either by electric welding or 60 by the blow-pipe process after removing the temporary fish-plates.

65 After the completion of the molecular unions and the cooling down of the rail-ends the spanning-plate C and the spanning-fish-plates 12 and 13 may be attached

to the rail-ends A and B according to the previously described process involving a preliminary expansion of the plates by heating or in any suitable manner.

Even when the spanning-plates at the 70 joint are not under tension, their combination in the joint with the molecular union of the rail-ends completes a very effective strain resisting joint. Likewise the spanning-plate crossing the rail-joint and connected beneath and to the feet of the abutting rail-ends to draw the same into close 75 abutting contact by its normal tension, is itself of importance within the invention.

It is, of course, to be understood that the 80 normal tension of the spanning-plates may be produced in any efficient manner, the process of heating and cooling being merely 85 illustrative, while eccentric pins and drive pins with staggered holes are both illustrations of other modes of accomplishing the result.

What is claimed and what is desired to be secured by United States Letters Patent is:

1. A rail joint comprising abutting rail- 90 ends, a joint-spanning plate mechanically connected directly to the abutting rail-feet; and a molecular union connecting the abutting rail-heads.

2. A rail joint comprising abutting rail- 95 ends, a joint-spanning plate mechanically connected directly to the abutting rail-feet; one or more joint-spanning fish-plates mechanically connected with the abutting rail-webs; and a molecular union connecting 100 the abutting rail-heads.

3. A rail joint comprising abutting rail- 105 ends, a joint-spanning plate mechanically connected directly to the abutting rail-feet; a molecular union connecting the abutting rail-feet; and a molecular union connecting the abutting rail-heads.

4. A rail joint comprising abutting rail- 110 ends, a joint-spanning plate mechanically connected directly to the abutting rail-feet; a molecular union connecting the abutting rail-feet; a molecular union connecting the abutting rail-webs; and a molecular union connecting the abutting rail-heads.

5. A rail joint comprising abutting rail- 115 ends, a joint-spanning plate mechanically connected directly to the abutting rail-feet; one or more joint-spanning fish-plates mechanically connected with the abutting rail-webs; a molecular union connecting the 120 abutting rail-feet; and a molecular union connecting the abutting rail-heads.

6. A rail joint comprising abutting rail- 125 ends, a joint-spanning plate mechanically connected directly to the abutting rail-feet; one or more joint-spanning fish-plates mechanically connected with the abutting rail-webs; a molecular union connecting the abutting rail-feet; a molecular union connecting the abutting rail-webs; and a molec- 130

ular union connecting the abutting rail-heads.

7. A rail joint comprising abutting rail-ends, a joint-spanning plate normally under tension mechanically connected directly to the abutting rail-feet; and a molecular union connecting the abutting rail-heads.

8. A rail joint comprising abutting rail-ends, a joint-spanning plate mechanically connected directly to the abutting rail-feet; one or more joint-spanning fish-plates mechanically connected with the abutting rail-webs; and a molecular union connecting the abutting rail-heads, said joint-spanning plates being normally under tension to place the joint under normal compression.

9. A rail joint comprising abutting rail-ends, a joint-spanning plate in the form of an inverted rail with its foot mechanically connected directly to the abutting rail-feet; and a molecular union connecting the abutting rail-heads.

10. A rail joint comprising abutting rail-ends, a joint-spanning plate in the form of an inverted rail with its foot mechanically connected directly to the abutting rail-feet; one or more joint-spanning fish-plates mechanically connected with the abutting rail-webs; and a molecular union connecting the abutting rail-heads.

11. A rail-joint having the abutting rail-ends held normally under compression by a

steel joint-spanning plate normally under tension and mechanically connected directly to the under faces of the abutting rail-feet. 37

12. A rail joint having the abutting rail-ends held normally under compression by a steel joint-spanning plate normally under tension and mechanically connected directly to the under faces of the abutting rail-feet, 40 said plate being an inverted short length of rail.

13. A rail joint having the abutting rail-ends held normally under compression by a steel joint-spanning plate normally under 43 tension and mechanically connected directly to the under faces of the abutting rail-feet; and fish-plates connecting the abutting rail-webs.

14. A rail joint comprising abutting rail-ends, one or more joint-spanning fish-plates mechanically connected with the abutting rail-webs, a molecular union connecting the abutting rail-feet; a molecular union connecting the abutting rail-webs, and a molecular union connecting the rail-heads.

In witness whereof, I have signed my name to this specification, in the presence of two subscribing witnesses.
